CLAIM

The ornamental design for a distance finder, as shown and described.

DESCRIPTION

FIG. 1 is a front elevational view of the design;
FIG. 2 is a rear elevational view of the distance finder in FIG. 1;
FIG. 3 is a bottom side elevational view of the distance finder in FIG. 1;
FIG. 4 is a top side elevational view of the distance finder in FIG. 1;
FIG. 5 is a left plan view of the distance finder in FIG. 1;
and,
FIG. 6 is a right plan view of the distance finder in FIG. 1.
